UNITED STATES PATENT OFFICE

145,108

DESIGN FOR A COMBINATION TOASTER AND COOKER

Otto E. Stelzer, German Township, St. Joseph County, Ind., assignor to Calkins Appliance Corporation, South Bend, Ind., a corporation of Indiana

Application August 1, 1945, Serial No. 121,129

Term of patent 14 years

(Cl. D81—10)

To all whom it may concern:

Be it known that I, Otto E. Stelzer, a citizen of the United States, residing in German Township, in the county of St. Joseph, State of Indiana, have invented a new, original, and ornamental Design for a Combination Toaster and Cooker, of which the following is a specification, reference being had to the accompanying drawing, forming part thereof.

The figure is a perspective view showing the top,

front and one side of a combination toaster and cooker embodying my design. The left side of the device is like the right side shown, and the back is substantially like the front with the exception that the handle shown on the front is omitted therefrom.

I claim:

The ornamental design for a combination toaster and cooker, as shown and described.

OTTO E. STELZER.
